LUMINAIRE

Thomas W. Rolph, Newark, Ohio, assignor to
Holophane Company, Inc., New York, N. Y., a
corporation of Delaware

Application November 2, 1944, Serial No. 561,511

4 Claims. (Cl. 240—103)

1

The present invention relates to luminaires, and is more particularly directed toward luminaires employing elongated light sources such as fluorescent lamps and having reflecting troughs to direct the light downwardly.

For optimum distribution of reflected light the reflector has heretofore been made of specular reflecting sheet metal with a smooth contour and quite generally provided with a cusp back of the lamp so as to deliver the reflected light in directions to miss the opaque lamp.

The present invention contemplates a luminaire having a lamp and reflector with substantially the same effective redistribution of light as is accomplished by a specular metal reflector, such, for example, as the one just referred to, and wherein the new reflector is made of flat or nearly flat elements of transparent material ribbed either internally or externally and mirrored to control the redirection of the light. These reflectors are typically mirrored glass which may be pressed flat or nearly flat and assembled in the desired position.

The accompanying drawings show, for purposes of illustrating the present invention, two embodiments in which the invention may take form, it being understood that the drawings are illustrative of the invention rather than limiting the same.

In these drawings:

Figure 1 illustrates a typical form of specular reflector with fluorescent lamp showing a typical contour and light redirection by such reflector;

Figures 2 and 3 are cross sectional views through luminaires with the mirrored reflectors, the ribs being external; and

Figure 4 is a fragmentary view of an internally ribbed mirrored reflector.

In Figure 1 the light source 10 is illustrated in the form of a single tubular lamp, but, of course, two or more lamps may be employed as customary. A conventional reflector form is illustrated at 11, this form being considered as a corresponding form for the reflectors illustrated in Figures 2 and 3 which are substantially the optical equivalent.

In Figure 1 light rays have been drawn from the center of the light source at every 10° from 70° to 170° above the nadir and the corresponding specularly reflected light rays indicated at 12. It will be apparent that such a reflector directs all the reflected light out through its mouth, the light from the upper part of the reflector being directed away from the nadir to miss the lamp, while the light from the lower part of the reflec-

2

tor is directed downwardly and across the axis of the luminaire.

In Figure 2 the light source is again indicated at 10 and the reflecting trough is composed of an upper flat member 13 and two flat side members 14, 14. These, as above mentioned, are typically pieces of pressed glass. The upper piece has a series of prism-like elements 13a, 13b, 13c, 13d, 13e, 13f, 13g, 13h, 13i, 13j, with surfaces tipped to the horizontal plane of the lower surface. The upper part of the side member 14 has similar prism-like ribbings 14a, 14b, 14c, 14d, 14e, 14f, 14g, whose upper surfaces are tipped to the plane of the inner or lower surface. The entire outer or upper surface of the reflector is mirrored, as indicated by the letter M.

The light rays from the 70° to 170° angles above the nadir are redrawn the same as in Figure 1,

and it will be noted that these light rays enter

the transparent medium, i. e., the glass of the

reflectors, pass to the outer reflecting surface

and are reflected back into the glass and trans-

mitted into the air at angles which differ from

what the angles would have been had there been

no tipping of the reflecting surfaces. This re-

flection takes place, as indicated in the drawing

by the lines 15 terminating in arrows, and it will

be seen that the action is substantially the same

as that produced by the smooth, specular reflec-

tor of Figure 1; that is to say, the light emitted

in the region of zenith is reflected downwardly

and away from the nadir so as to escape between

the lamp and the outer part of the reflector,

while the light which strikes the side members

14, 14 is reflected downwardly and toward the

fixture axis in the same way as the correspond-

ing direct light was reflected by the reflector of

Figure 1.

In Figure 2 the lower part of the side pieces

14, 14 has the same contour and position as the

lower part of the reflector 11 of Figure 1, and

hence this reflector need have no external prism-

like ribs. For purposes of comparison the por-

tion of the curved reflector 11 intercepting the

same zone of direct light rays as the ribbed mir-

rored reflector is indicated in dotted lines, and

the reference character 11 is applied. If the

mirrored reflector were smooth and followed the

same contour as the metal specular reflector, the

redistribution of the light would be the same as

in Figure 1. Manufacturing limitations make it

impossible to economically make such curved re-

flectors of the size required. The same

optical effect is obtained according to the present

invention by tipping the reflecting faces of the

prism-like ribs so as to bring them to approximately the same slope as the opposed portion of curve 11. These tipped surfaces do not come into exactly the same slope, because of the deviations in light reflection caused by the refraction on entering and on leaving the transparent medium. This relocation of the reflecting surface in steps out of parallelism with the incident surface makes it possible to have the equivalent of a flat reflector with thin sections.

In the form shown in Figure 3 the reflector comprises two flat sloping plates 20. The portions of these plates falling inside the curve 11 have regressed prism-like ribbings 21 mirrored, as shown, and these redirect the light rays, as shown at 23, in practically the same way as the part of the specular surface 11 occupying the same angle about the lamp. The portions 22 of the plates 20 above curve 11 have similar prism-like mirrored ribbings and they reflect the light as indicated at 23.

It will be understood that the mouth of the reflector will usually be provided with a suitable cover or closure where it is desired to further control the direct and reflected light, but as such or closure forms no part of the present invention it is omitted from the drawings.

It is also possible to have the regressed prisms in the incident surface as indicated at 24 in Figure 4. The reflected ray 25 has a different path than it would have had but for the ribbing.

Since it is obvious that the invention may be embodied in other forms and constructions within the scope of the claims, I wish it to be understood that the particular forms shown are but a few of these forms, and various modifications and changes being possible, I do not otherwise limit myself in any way with respect thereto.

What is claimed is:

1. The combination with a horizontal rectilinear fluorescent lamp of an inverted trough-shaped reflector about said lamp for obtaining from the lamp substantially the same distribution of reflected light originating in the lamp as that obtained from an inverted trough-shaped specular reference reflector parallel with the lamp and occupying a predetermined position in space and having a smooth profile which includes downwardly and outwardly diverging sides and a cusped inwardly concave upper portion shaped to reflect high angle direct light downwardly and outwardly past the lamp, comprising flat transparent plates of generally uniform thickness parallel with the source, disposed to form an inverted trough and occupying a different position in space than the reference reflector but intercepting the same zone of direct light, the plates being externally mirrored to interiorly reflect light incident on their outer surfaces at angle less than the critical angle, one surface of each plate being smooth, the other having over at least a portion thereof, relatively narrow side by side rib forming areas tilted to the smooth surface in variant amounts such that the angles of refraction of entering rays differ from the angles of incidence of corresponding reflected rays on the emitting surface to such an extent that the emitted rays are substantially parallel to the corresponding reflected rays which the

smooth profile reference reflector would have produced.

2. The combination with a horizontal fluorescent lamp of a trough-shaped reflector symmetrical about a vertical plane through the source, the reflector being composed of flat externally mirrored glass plates each having a smooth surface and an opposed surface comprising at least in part a series of adjacent tilted areas regressed to a plane parallel with the smooth surface, the angle of tilt of the areas varying from area to area such that the over all deviation accomplished by refraction at the incident surface followed by reflection at the mirrored surface and refraction at the emergent surface is substantially equal to the deviation obtainable by specular reflection of corresponding direct rays by a trough-shaped reflector of a smooth profile occupying a different position in space and having straight sides and a cusped inwardly concave top.

3. The combination with a rectilinear horizontal fluorescent lamp of an inverted trough-shaped reflector about the lamp and comprising a horizontal flat plate and two downwardly and outwardly sloping side plates, the plates being transparent and externally mirrored and having one surface smooth, the horizontal plate having at each side of the vertical plane through the lamp a series of prismatic ribs parallel with the lamp and of variant angle of tilt to the smooth surface to reflect light downwardly and outwardly to pass down laterally of the lamp, the upper portions of the side plates having a series of prismatic ribs of variant angle of tilt to the smooth surface and less steep than the smooth surface to reflect light downwardly and inwardly to cross said vertical plane.

4. The combination with a rectilinear horizontal fluorescent lamp of an inverted trough-shaped reflector about the lamp and comprising two flat plates sloping at the same angle to the vertical and meeting above the lamp center, the plates being externally mirrored, one side of each plate being smooth, the other side having adjacent tilted areas regressed to a plane parallel to the smooth surface, the areas below a region substantially level with the lamp center being steeper than the smooth surface and emitting light generally downward, the areas immediately above this region being less steep than the smooth surface and emitting light generally downward laterally of the lamp, the areas adjacent the vertex of the plates being steeper than the smooth surface and reflecting high angle vertical light onto the other plate.
